US0D1042570S

(12) **United States Design Patent** (10) **Patent No.:** **US D1,042,570 S**
(45) **Date of Patent:** **** Sep. 17, 2024**

(54) **VACUUM SEALER**

(71) Applicant: **Shenzhen Aipu Electronics Technology Co., Ltd.**, Guangdong (CN)

(72) Inventor: **Kunhua Chen**, Guangdong (CN)

(73) Assignee: **Shenzhen Aipu Electronics Technology Co., Ltd.**, Guangdong (CN)

(**) Term: **15 Years**

(21) Appl. No.: **29/832,644**

(22) Filed: **Mar. 29, 2022**

(30) **Foreign Application Priority Data**

Oct. 11, 2021 (CN) 202130665449.0

(57) **CLAIM**

The ornamental design for a vacuum sealer, as shown and described.

DESCRIPTION

FIG. 1 is a front, right and top perspective view of a vacuum sealer, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines in the drawings depict portions of the vacuum sealer that form no part of the claimed design.

1 Claim, 8 Drawing Sheets
